UNITED STATES PATENT OFFICE

2,442,394

BLOWTORCH WITH CONTINUOUSLY BURNING VAPORIZOR AND IGNITER

Horace L. Baum, St. Louis, Mo.

Application April 13, 1945, Serial No. 588,164

7 Claims. (Cl. 158—35)

1

This invention relates to blowtorches and more particularly, to an alcohol blowtorch.

A main object of the invention is to provide a novel and improved alcohol blowtorch.

A further object of the invention is to provide an improved alcohol blowtorch of simple construction wherein improved means for developing and maintaining blast pressure within the torch is provided.

Further objects and advantages of the invention will appear from the following description and claims, and from the accompanying drawings, wherein:

Figure 1 is a side elevational view partly in section of an improved blowtorch in accordance with this invention.

Figure 2 is a rear elevational view of the blowtorch of Figure 1.

Figure 3 is a detail view of the securing gland for the neck of the blowtorch of Figure 1.

Referring to the drawings, 1 designates the body portion of the blowtorch. Body portion 1 comprises a container divided into two compartments comprising an upper compartment 2 and a lower compartment 3. Each of the compartments is adapted to contain a supply of liquid fuel such as alcohol.

Secured to the top wall of body portion 1 and extending into compartment 2 is a curved rigid tube 4 of copper or similar heat-conducting material, terminating at its upper end in a hollow tip member 5. The securing means for tube 4 comprises a gland assembly consisting of a threaded bushing member 6 in threaded engagement with a boss 7 integral with or rigidly secured by welding, brazing or similar means to the top wall of body portion 1. An appropriate bore is formed in boss 7 through which tube 4 passes, said tube also passing through bushing 6, as shown in Figure 3. A rigid washer 8 is provided under bushing 6 and a deformable annular gasket 9 is provided between washer 8 and the top surface of boss 7. Tightening bushing 6 compresses gasket 9 to effectively seal tube 4 with respect to compartment 2.

A handle member 10 is provided for the blowtorch, the lower end of said handle being received in a bracket 11 rigidly secured to body portion 1, the upper end of said handle being formed with an annular portion providing an opening through which boss 7 is received, a nut 12 being threaded on to boss 7 to firmly secure the annular top portion of handle member 10 to said boss.

Contained within tube 4 is a smaller tube 13 of copper or similar material, tube 13 being sur-

2

rounded by a fibre glass wicking sleeve 14. The lower end of tube 13 extends to a position slightly above the bottom of compartment 2, whereas the lower ends of tube 4 and sleeve 14 extend to a position a short distance above the lower end of tube 13, as shown in Figure 1. The fuel level in compartment 2 is normally well above the lower ends of tube 4 and sleeve 14.

The upper ends of tube 13 and sleeve 14 extend into tip 5, said tip being formed with a restricted orifice 15. As shown in Figure 1, tube 4 is appropriately curved so that tip 5 and its orifice 15 are approximately horizontally directed.

Rigidly mounted on the top wall of body portion 1 under tube 4 is an inclined sleeve member 16 formed with a short branch element 17. Communicating with the bore of sleeve 16 is an internal sleeve member 17 provided in compartment 2 and leading into compartment 3. A wick member 18 is provided in compartment 3, said wick member 18 passing upwardly through internal sleeve member 17 into inclined sleeve member 16, said wick member being divided at its upper portion so that part thereof extends through sleeve 16 to the top open end of said sleeve 16 and the other part extends through short sleeve 17 to the top open end of said short sleeve. A deflector shield 19 is pivotally secured to the top end of sleeve 16 for directing the flame from the wick into the fuel jet discharge from orifice 15.

Compartment 3 is filled with fuel by a filler plug 20 provided in the container wall, as shown in Figures 1 and 2.

Compartment 2 is filled with fuel through boss 7, bushing 6 and tube 4 being removed during the refueling process.

To operate the blowtorch, the wick 18 is ignited at the top of tube 16 and tube 17. The flame from tube 17 heats tube 4 and vaporizes the fuel which has been drawn by capillary action into fibre glass sleeve 14, causing a building up of pressure in compartment 2 which, combined with capillary action, forces fuel upwardly through small tube 13 and projects it out through restricted orifice 15. Said outwardly projected fuel forms a jet which is ignited by the flame from the top of sleeve 16. The discharge of vapor is considerably restricted by orifice 15 so that a substantial pressure may be built up in compartment 2. The refractory characteristics of fibre glass wick 14 prevent its ignition, and consequently no clogging of orifice 15 by products of combustion thereof occurs. This feature is highly advantageous, since in torches of the prior art the wicking disintegrates at the burner tip

causing clogging of said tip and necessitates frequent dismantling of the burner for cleaning.

It is readily apparent that by pre-heating the vapor in the refractory sleeve in tube 4 vapor pressure is developed in compartment 2 which is self-maintained by the flame at the top of sleeve 17. It is thus unnecessary to pump air into the pressure chamber as is done in conventional blowtorches.

The size and temperature of the torch flame may be regulated by the use of burner tips having orifices of appropriate size, so that the jet pressure and quantity of fuel ejected may be adapted to the specific character of torch flame desired.

While a specific embodiment of a blowtorch has been described in the foregoing description, it will be understood that various modifications within the spirit of the invention may occur to those skilled in the art. Therefore it is intended that no limitations be placed on the invention other than as defined by the scope of the appended claims.

What is claimed is:

1. A blowtorch comprising a fuel container, a heat conducting conduit extending from said container and provided at the end remote from said container with a restricted orifice, a fuel feed tube contained within said conduit and extending from adjacent said orifice into said container below the fuel level therein, a wicking sleeve being provided on said fuel feed tube for a substantial portion of the length thereof and extending into the fuel in the container, said wicking sleeve being of refractory material, and means for continuously heating said conduit during operation of the blowtorch.

2. The structure of claim 1, and wherein said wicking sleeve is made of glass fibre.

3. The structure of claim 1, and wherein said heating means comprises an auxiliary fuel container provided with a burner positioned adjacent said conduit.

4. A blowtorch comprising a body portion containing a first fuel compartment and a second fuel compartment, a conduit of heat conducting material extending from said first fuel compartment and provided with a restricted orifice at the end remote from said first fuel compartment, a fuel feed tube contained within said conduit and extending from adjacent said orifice into said first fuel compartment below the fuel level therein, a wicking sleeve of refractory material

provided on said fuel feed tube for a substantial portion of the length thereof and extending into the fuel in said first fuel compartment, and a burner on said body portion adjacent said conduit embodying an inclined sleeve member having a short-branch element communicating with said second fuel compartment, said short-branch element being adapted to provide a flame for continuously heating said conduit during operation of the blowtorch.

5. The structure of claim 4, and wherein said wicking sleeve is made of glass fibre.

6. The structure of claim 4, and wherein the top portion of the inclined sleeve member is adapted to provide a flame at said restricted orifice, means being provided on the top portion of said inclined sleeve member for directing said flame.

7. A blowtorch comprising a body containing a first fuel compartment and a second fuel compartment, a conduit of heat conducting material extending from said first fuel compartment and provided with a restricted orifice at the end remote from said first fuel compartment, a fuel feed tube contained within said conduit and extending from adjacent said orifice into said first fuel compartment below the fuel level therein, a wicking sleeve of refractory material between said conduit and fuel feed tube and extending into said first fuel compartment, sealing means between said conduit and body, a handle connected to said sealing means and body, and a burner on said body adjacent said conduit and adapted to continuously heat said conduit during operation of the blowtorch.
